ATTORNEY.

UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR LOCK.

Application filed March 13, 1923. Serial No. 544,847.

To all whom it may concern:

Be it known that I, NORMAN B. HURD, a citizen of the United States of America, residing at New Britain, Connecticut, have 5 invented a new and useful Door Lock, of which the following is a specification.

My invention relates to improvements in locks which are particularly useful for automobile doors. My object is to provide a 10 construction that is simple, inexpensive, and capable of easy and sure operation. The construction is also such that the outer knob may be securely locked from the inner side of the door against movement.

15 In the drawings:

Fig. 1 is a side elevation, partly broken away, of my improved lock.

Fig. 2 is a similar view showing the parts in different position.

20 Fig. 3 is a detail view.

1 represents a lock case within which the various parts are housed. 2 represents the face plate through which a spring latch bolt head 3 projects. The latch is normally impelled forwardly by a suitable spring such as indicated at 4. 5 is a latch retracting lever of the bell crank type, the same being pivoted to the case at 6 the lower end engaging said latch. 7 is a spring which serves 25 to move the latch retracting lever in one direction. 8 is a roll-back arm arranged to engage the upper end of the bell crank 5 to move it in the opposite direction. 9 is a suitable handle at the indoor side of the 30 lock, the same being connected with the hub of the roll-back arm 8. 10 is a yielding detent arm the nose of which bears against a shoulder 8^a on the roll-back hub back of the arm 8 to frictionally hold the handle 9 in the position shown in Fig. 1, or in the 35 position shown in solid lines in Fig. 2. 11 is a second roll-back arm arranged to engage a shoulder 5^a on the bell crank latch retracting lever 5. The hub of the roll-back arm 11 is suitably mounted in the case 1, and is connected to an outside knob spindle or equivalent device.

When the parts stand as shown in Figure 1, it is obvious that by moving the inside handle 9 in the direction indicated by the arrow, the lever 5 will be tilted by the roll-back arm 8 in a direction to retract the latch, since the lower end of the lever 5 will then

engage a shoulder 3^a on the latch and impart said retracting movement to the latter. 65

The latch retracting lever 5 may also be tilted to extract the latch by moving the outside roll-back arm 11 in the direction indicated by the arrow.

Should it be desired to set the mechanism 80 so that the latch cannot be retracted by the outside roll-back arm 11, the inside handle 9 is moved abnormally or in a direction opposite to that indicated by the arrow in Fig. 1, that is to say, it may be moved into the 85 position shown in solid lines in Fig. 2, in which position a solid portion of the roll-back hub which carries the arm 8 presents itself closely in front of the adjacent end of the latch retracting lever 5, as clearly 90 seen in Fig. 2. Manifestly in this position, the retracting lever 5 cannot be rocked by the outside operated roll-back arm 11 and hence the door will be locked. When the handle 9 is restored to the position shown in Fig. 1, a recess 12 in the roll-back hub will be presented in front of the adjacent end of the latch retracting lever 5 so that 95 adequate clearance will be provided to permit said lever 5 to be locked by the arm 11 or arm 8. In the dotted lines shown in Fig. 2 I have indicated how the friction detent 10 is represented when the handle 9 is being moved into the locking position and how 100 said detent holds said arm in said position against accidental displacement. The spring 7 serves to operate both the lever 5 and the detent 10.

By this construction the knob or handle for pulling the door open from the outside 105 may be located very close to the edge of the door, as shown by the location of the roll back 11, all of which permits the power required to pull the door open to be applied most advantageously. Again, it permits the 110 handle for the inside to be located farther away from the edge of the door, so that there will be no danger of said handle striking the door casing as the door is being opened or closed.

115 What I claim is:

1. In a lock, a case, a spring projected latch bolt carried thereby, means at the indoor side of said case for manually retracting said latch and means at the outdoor side 120 of said case for manually retracting said

latch and cooperating means including a pivoted latch retracting lever between said parts whereby an abnormal movement of the first mentioned retracting means will lock the parts against latch retraction from the outdoor side of the lock, said retracting means engaging said lever at opposite sides of the pivotal center.

2. In a lock, a case, a spring projected 10 latch bolt, a latch retracting lever, two separately and independently rotatable roll backs coacting with said lever to retract the latch, said roll backs being accessible from opposite sides of a door to which the lock 15 is applied, one of said roll backs when in one position operating to block said latch retracting lever and prevent the retraction of the latch by the other roll back, and means to frictionally hold said lever blocking roll back in said blocking position.

3. In a lock, a case, a retractable latch bolt carried thereby, a single latch retracting lever, two separate roll-backs coacting with said lever to operate the same whereby 25 said latch may be retracted by either of said roll-backs, one of said roll-backs operating when in one position to permit said lever to be freely moved by the other roll-back and when in another position operating 30 as a stop against said lever to prevent movement of said lever by said other roll-back, with means for holding said lever

blocking roll back in the lever blocking position against unintentional displacement.

4. In a door lock, a case, a spring projected latch bolt at the face of said case, a latch retracting lever mounted in said case, means at the outdoor side of said case and close to the face thereof for engaging said latch retracting lever to tilt the same and 40 retract the latch, and other means at the indoor side of the case for engaging said lever at a point more remote from the face of the lock than the first-mentioned means, said indoor retracting means operating to move the lever and retract the latch when turned in one direction, and operating to block said lever against movement when turned in an opposite direction.

5. In a lock, a retractable latch bolt, a pivoted latch bolt retracting lever co-acting therewith, two independently operable devices for operating said lever from opposite sides of the lock in the latch retracting direction, one of said devices when moved in one direction away from a neutral position co-acting with said lever to retract the latch, a shoulder carried by said device co-acting with said lever when said device is turned in an opposite direction to lock said lever 50 against movement in a latch retracting direction by the other device.

NORMAN B. HURD.
